ABSTRACT OF THE DISCLOSURE

A tip-up bed and table combination having a pivotally mounted spring mattress movable between a substantially horizontal use position and a substantially vertical storage position. At least one panel is movably mounted between a first position concealing the stored bed and a second substantially horizontal position wherein the panel serves as a table.

The present invention has for its object to provide a tip-up bed comprising a spring-mattress pivotally mounted in order to be able to take up a substantially horizontal position when in use and a substantially vertical position for storage, at least one panel being mounted on this spring-mattress in order to conceal it when it takes up its storage position.

The invention aims at providing a table combined with a tip-up bed. This combination of a bed and a table is of particular interest when furnishing premises of limited space, wherein it often proves difficult to fit in essential pieces of furniture, this combination affording the great advantage of permitting the storage of two pieces of furniture, of large dimensions, within a very small volume and to provide thereby, when these pieces of furniture are not used, a considerable free space in the premises where they are available.

For that purpose, according to the invention, at least one part of the said panel is articulated on the spring-mattress so as to be able to take up a position substantially at right angles to the latter when it is in the storage position. Means are provided, on that part of the panel, to support it when it takes up its position at right angles to the spring-mattress, this part of the panel being intended to be used as a table.

According to a form of embodiment of the invention, the said panel comprises two parts extending on either side of a transverse member fastened to the spring-mattress, this transverse member being parallel to the longitudinal axis of the latter. Each of the parts of the panel are mounted on a hinge on the transverse member so as to be able to pivot, in opposite directions, to take up a position substantially at right angles to the spring-mattress. The top part of the panel, looking at the bed in the storage position, being intended to take up its position at right angles to the spring-mattress, to support the latter, when the spring-mattress is turned down in the horizontal position for use. The lower part of the panel, in order to be used as a table, is intended to take up its position at right angles to the spring-mattress when the latter is in the storage position.

According to an advantageous form of embodiment of the invention, locking means are provided and are fitted so as to lock, on the one hand, the part of the panel which can be used as a table, when the spring-mattress takes up its horizontal position when in use and, on the other hand, the spring-mattress in the storage position, when the said part of the panel is used as a table.

According to a particularly advantageous form of embodiment of the invention, the said means are fitted so as

2

to lock the part of the panel used as a support for the spring-mattress when it takes up its position at right angles to the latter and when this spring-mattress is in the horizontal position for use.

Other details and features of the inventions of the invention will become apparent from the description of the drawings accompanying the present specification and which show, by way of non limitative example, a particular form of embodiment of the object of the invention.

FIGURE 1 is a view in perspective of the tip-up bed and of the said table in the storage position.

FIGURE 2 is a view in perspective of the bed in the position for use.

FIGURE 3 is a view in perspective of the bed in the storage position and of the table in position for use.

FIGURE 4 is a view in perspective showing the said locking means.

FIGURE 5 is a view in elevation, on a larger scale, partially broken away, of a detail of the locking means.

In the different figures, the same reference numerals refer to similar elements.

The bed shown in the drawings comprises a pivotally mounted spring-mattress 1, fitted inside a frame 2, on which is fastened a panel 3 so as to conceal it when it takes up its storage position (FIGURE 1). The panel 3 comprises two parts 4 and 5 extending on either side of a transverse member 6 integral with the said spring-mattress. The transverse member 6 is secured to the spring-mattress parallel to the longitudinal axis of the latter and the parts 4 and 5 of the panel 3 are mounted with articulation at points 7, on this transverse member so as to enable them to pivot in opposite directions according to the arrows 8 and 9, to take up a position substantially at right angles to the spring-mattress 1. The part 4 of the panel 3 is intended to take up its position at right angles to the spring-mattress, in order to support the latter when it is turned in position for use (FIGURE 2). The part 5 of the panel 3 is intended to take up its position, for use as a table, at right angles to the said spring-mattress, when the latter is in the storage position (FIGURE 3). Two legs 10 are associated with the part 5 of the panel in order to support it when it is being used as a table. Each of these legs is mounted by a hinge between one of their ends and the face of the said part of the panel facing the spring-mattress 1. The legs may be folded down, in accordance with the arrows 11, against the said part of the panel when the latter is brought back against the spring-mattress 1.

Locking means 12 are provided and fitted to the bed so as to lock, on the one hand, the part 5 of the panel 3 when the spring-mattress 1 takes up its position for use and, on the other hand, the spring-mattress, in the storage position, when the part 5 of the panel is used as a table. The locking means 12 are also fitted so as to lock the part 4 of the panel 3 used as a support for the spring-mattress 1 when it takes up its position at right angles to the latter and when this spring-mattress is in position for use. In the FIGURE 4, the locking means are shown in full lines in the position 16 they take up when assuring the locking of part 5 of the panel 3, the spring-mattress 1 being able to pivot freely with reference to the frame 2. The locking means 12 are also shown, in dot and dash lines, in the position 17 they take up to assure the locking of the spring-mattress 1 in the frame 2, the part 5 of the panel 3 being then able to pivot around the transverse member 6. The locking means 12, provided to prevent any wrong movement of the bed or of the table, comprise a stem 13, the axis thereof being parallel to the transverse axis of the spring-mattress. This stem 13 is mounted on the spring-mattress, by means of a component 14 integral with the spring-mattress and of a component 15 integral with the transverse member 6, and is

guided in these components so as to be able to slide along its own axis with reference to the said spring-mattress. The stem 13 is driven, in order to move between two end positions 16 and 17, by a tie-rod 18 articulated, on the one hand, at 23, on the stem 13 and, on the other hand, at 24, on the part 4 of the panel 3. The tie-rod 18 is fitted so that, when the part 4 of the panel 3 takes up its position at right angles to the spring-mattress, the end 19 of the stem cooperates with a member 20, secured to the part 5 of the panel 3, so as to make this part 5 of the panel integral with the spring-mattress 1, the end 21 of the stem 13 being then released from an element 22 integral with the frame 2, this position 16 of the stem 13 making it possible to bring the spring-mattress 1 into its position for use. When the spring-mattress 1 takes up its storage position and when the part 4 of the panel 3 is turned down against the spring-mattress, the tie-rod 18 drives the stem 13 so as to make it take up its position 17. In that position the end 19 of the stem is released from the member 20 while the end 21 cooperates with the member 22 of the frame 2, the spring-mattress 1 being then locked in the frame 2 while the part 5 of the panel 3 can be released for use as a table. When the stem 13 takes up its position 17, its end 19 remains engaged, over a very slight distance, in the member 20 (FIGURE 5). A spring 25, the end 26 thereof being integral with the component 15 while the end 27 thereof is integral with the stem 13, keeps the end 19 of the stem inside the member 20. The articulation 23 of the stem on the tie-rod 18 permits, without movement of the latter, a slight displacement of the stem, the length of this displacement being at least equal to the length of the portion of the stem 13 remaining engaged inside the member 20. The end 19 of this stem is shaped so that the said stem may be released from the member 20, against the action of spring 25, when a pull is applied to the part 5 of the panel 3 in order to bring it into the position in which it will serve as a table. This fitting offers the advantage of permitting part 5 of the panel 3 to be maintained against the spring-mattress 1, when this part is unlocked and when its use as a table is not wanted.

In order to insure the locking of part 4 of the panel 3 when it takes up its position at right angles to the spring-mattress and when the latter is in the position of use, a rocker 28, articulated in 29 on a component (not shown) of the spring-mattress 1, cooperates with a lug 30 integral with the stem 13. This lug fits into a notch 31 of the rocker, when the latter moves according to arrow 32 and is blocked by the rocker which results in immobilizing the stem 13, the tie-rod 18 as well as the part 4 of the panel 3. The rocker 28 is fitted so that the lug 30 may be released from the notch 31 when the spring-mattress 1 takes up its vertical ranging position.

It must be understood that the invention is in no way limited to the form of embodiment described and that many changes may be made to the latter without departing from the scope of the present patent application.

It might, for example, be contemplated to use the whole of the panel 3 as a table, means being provided so as to enable the articulations of the said panel to be displaced with reference to the spring-mattress. It might also be contemplated not to use the whole of the said part 5 of the panel 3 as a table.

We claim:

1. A tip-up bed comprising:
a frame;
a spring-mattress pivotally mounted on said frame;
at least one table forming panel being mounted on said spring-mattress for rotation about an axis substantially parallel to the longitudinal axis of the spring-mattress, means being provided to selectively main-

tain said table forming panel in a position substantially at right angles to the spring-mattress; at least one support forming panel mounted on said spring-mattress for rotation about an axis parallel to above-mentioned axis, means being provided to selectively maintain said support forming panel in a position substantially at right angles to the spring-mattress;

said table forming panel being adapted to be used as a table when said bed is in its stored position and said support forming panel being adapted to support the bed when said bed is in a horizontal position.

2. A tip-up bed according to claim 1 further comprising: a transverse element substantially parallel to said longitudinal axis and integral with said spring-mattress; both said panels being pivotally mounted on said element, the table forming panel being adapted to rotate in a direction opposite to that of the support forming panel.

3. A tip-up bed according to claim 2 further comprising locking means, said locking means comprising:

a stem slidably mounted on the spring-mattress; a first member integral with the table forming panel adapted to cooperate with the stem to lock the table forming panel against the spring-mattress;

a second member integral with the frame, adapted to cooperate with the stem to lock the spring-mattress in its stored position;

said stem having two positions, the first where it cooperates with the first member to lock the table forming panel against the spring-mattress and the second where it cooperates with the second member to lock the spring-mattress in its retracted position.

4. A tip-up bed according to claim 3 further comprising: a tie-rod operatively connecting the stem to the support forming panel;

said tie-rod being adapted to slide the stem when the support forming panel is moved; the first position of the stem corresponding to the position of the support forming panel at right angles to the spring-mattress and the second position of the stem corresponding to the stored position of the support forming panel.

5. A tip-up bed according to claim 4 further comprising: spring means connected to the spring-mattress and to the stem, said spring means being adapted to maintain the stem, when in its second position, in slight cooperation with the first member.

6. A tip-up bed according to claim 5 further comprising a rocker articulated on the spring-mattress, said rocker having a notch:

a lug integral with said stem;
said lug being adapted to enter into said notch when said stem is in its first position locking said spring-mattress in a horizontal use position.

7. A tip-up bed according to claim 2 further comprising at least one leg member pivotally mounted on said table forming panel on the side remote from said transverse element, said member supporting said table panel in the use position.
